UNITED STATES PATENT OFFICE.

JAMES C. JARDINE AND JAMES DICKIE, OF SUMMERSIDE, PRINCE EDWARD ISLAND,
CANADA.

BRIDLE.

1,341,715.

Specification of Letters Patent.

Patented June 1, 1920.

Application filed February 24, 1919. Serial No. 273,974.

To all whom it may concern:

Be it known that we, JAMES C. JARDINE and JAMES DICKIE, both subjects of the King of Great Britain, residing at Summerside, Prince Edward Island, Canada, have invented certain new and useful Improvements in Bridles; and we do hereby declare that the following is a full, clear, and exact description of the invention, such 10 as will enable others skilled in the art to which it appertains to make and use the same.

The present invention relates to bridles and more particularly to a combination cheek and blind for bridles.

An object of the present invention is to provide a device of this character which will be strong, durable and efficient in use, and one which will be comparatively inexpensive in the cost of manufacture, thereby rendering the same commercially desirable.

With the above and other objects in view which will hereinafter appear as the description continues, the invention consists 25 of the novel features of construction, combination and formation of parts as will be hereinafter more fully described and particularly pointed out in the appended claim.

30 In the accompanying drawings:

Figure 1 is a side elevation of the combination cheek and blind embodying the present invention;

Fig. 2 is a section taken on the line 2—2 35 of Fig. 1 in the direction of the arrow as shown; and,

Fig. 3 is a section taken on the line 3—3 of Fig. 1.

The invention will be best understood 40 from a consideration of the following detailed description, taken in connection with the accompanying drawings forming part of this specification, with the further understanding that while the drawings show 45 a partial form of the invention, the latter is not confined to any strict conformity with the showing of the drawings, but may be changed and modified so long as such changes and modifications mark no material 50 departure from the salient features of the invention.

Like and corresponding parts are indi-

cated by similar reference characters throughout the several views.

The device consists of a reinforcing member 1 made of metal, preferably steel, which is provided with a projecting flanged portion 2 and a vertical strap portion 3 which is bent upon itself to form the loops 4 and a vertical parallel exteriorly extending strap 5. This metallic stiffening member may be placed to form the cheek of the blind and the cheek strap and is covered by means of an outer layer 6 and an inner layer 7 consisting of leather, which layers are stitched together as at 8. The strap 5 extends over the outer face of the layer 6 and extending through the straps 3 and 5 and the outer and inner layers are the rivets 9. Whereas we have illustrated rivets as fastening members, it is, of course, to be understood that screws, bolts or other suitable fastening members may be used equally as well. Secured to the upper loop 4 is a buckle 10 which may be connected to a strap of the 75 bridle and secured between the lower ends of the covering members 6 and 7 is a strap 11 which has its free end adapted to be connected to a buckle 12 carried by the lower loop 4.

80 From the foregoing it is obvious that this combined cheek strap and blind may be easily and readily attached to an ordinary bridle, thereby being able to be substituted for the cheek straps and blinds now in use. 85 By providing an inner stiffening member the blind cheek strap will retain its shape and thereby give a good appearance to the same and permit the same to be used for a greater length of time than ordinary blinds. 90

The outer metallic strap 5 is bent to form the loops 4 for attaching buckles to the bridle, but this outer metallic strap 5 may be bent upon itself to form other loops to admit the insertion of buckles when loopless 95 buckles are used upon the bridle.

Having thus fully described our invention, what we claim as new and desire to secure by Letters Patent is:

A combined cheek strap and blind comprising a metallic frame consisting of a winged portion having the configuration of a blind and an integral vertical strap portion having the configuration of a cheek

strap, a vertical strap section secured to said strap portion and extending parallel therewith, said vertical strap section being bent upon itself to form a loop at the upper end,
5 a buckle secured within said loop, the lower end of said strap section being looped over and connected to said frame, a buckle se-

cured within the lower strap section loop and a lower facing for said frame.

In witness whereof we have hereunto set 10
our hands.

JAMES C. JARDINE.
JAMES DICKIE.
